UNITED STATES PATENT OFFICE

LAWRENCE E. LENTZ, OF NEW YORK, N. Y., ASSIGNOR TO UNDERWOOD ELLIOTT FISHER COMPANY, OF NEW YORK, N. Y., A CORPORATION OF DELAWARE

TYPEWRITING MACHINE

Application filed April 1, 1930. Serial No. 440,677.

The present invention relates to tally-strip devices, such as are used on typewriting machines.

In practicing certain methods of bookkeeping, a wide record-sheet is held on the platen during the typing of a number of bills, the record-sheet preserving the carbon-copy of all the items of said bills.

It is also customary to type a tally-strip, 10 upon which appears line by line the items of all of the bills.

Thus the record-sheet keeps a complete record, while the tally-strip serves as a separate device for preserving the bare amounts of the 15 items.

It is usual to mount upon the typewriter-carriage a roll of paper which serves for such tally-strip. The type-impressions are usually made upon the tally-strip by use of carbon, 20 and the carbon is usually in the form of another strip, which pays off from another supply-spool.

The carbon-strip is usually imposed upon the tally-strip, and both run through the machine around the platen, between the platen and said wide sheet. That is, the tally-strip usually runs directly in contact with the platen, and is overlaid by the carbon-strip, and both are overlaid by the aforesaid record-sheet; and a carbon-sheet is interposed between said record-sheet and the main sheet or bill, upon which the typing is directly inked.

The bill is removed from the machine after 35 an item or set of items is typed thereon, and a fresh bill is inserted in place of it, without disturbing any of the remaining sheets. When the fresh bill is typed, carbon-copies thereof appear below the previously typed 40 lines upon the record and tally-strip, the platen having been duly advanced in order to secure proper line-spacing.

A little of the tally-strip with its carbon-strip is usually temporarily wound upon a 45 third spool. This third spool is usually driven by the line-spacing mechanism of the typewriter.

After a sufficient length of tally-strip has been typed, the typed portion together with 50 the carbon-strip may be pulled off from the

temporary winding spool, and the typed portion of the tally-strip may be torn off by means of a knife. Then the operator winds the surplus or partly used length of carbon-strip back onto the carbon supply spool. Rewinding of the used carbon-strip may take place before tearing off the typed tally-strip portion. 55

Before beginning to type the next bill, the leading end of the tally-strip, together with 60 carbon-strip, is properly caught upon the temporary winding spool, to be wound thereon by subsequent operation of the usual line-spacing mechanism. It is usual to tear off the tally-strip portion, before attaching the same, 65 together with carbon, to the temporary winding spool.

Typewriting machines for this class of work have usually been supplied individually with different capacities of strip mechanism, 70 that is, with capacities for different widths of strips. Where only one strip was to be used, the typewriting machine has been equipped accordingly, and if it were then desired to employ a different width of strip, 75 it was usually necessary to buy a new machine, especially equipped for the wider strip.

Thus according to former practice, it was necessary for every branch office of a typewriter manufacturing concern to carry in 80 stock as many sizes of tally-strip mechanisms as there were widths of tally-strip used, and it was necessary for machinists to install each tally-strip mechanism upon a typewriting machine before delivering it to the purchaser. 85

There has been heretofore devised a telescopic equipment, having extensible spools, etc., this telescoping giving a certain range of variation to the equipment, so that by means of a few equipments of different general capacities it became practicable to accommodate many widths of strip, thus reducing the number of sizes of equipments that it was necessary to manufacture and furnish. According to this telescoping plan, it became 90 practicable to enable a branch office to meet the needs of the customers without the necessity of carrying more than three different sizes of tally-strip mechanisms in stock. 95

According to said telescopic plan, each tal- 100

ly-strip was furnished upon a core of a length commensurate with the width of the strip, and the same was true of each carbon-strip, so that it was not necessary to provide for extending any cores, in adapting the machine for different widths of strip. The carbon-delivery spool and the tally-strip-delivery spool and the temporary winding spool were all carried in due relationship between a pair of mounts or side frames; and provision was made for adjusting these side frames towards and from each other along the platen or carriage of the typewriter, to accommodate different lengths of spools, thereby making it practicable to support any length of spools, carrying any width of strips, by means of the same side frames.

The platen frame or carriage carried a pair of tracks having the form of rods, which were mounted at their ends upon the ends of the platen-frame. Along these rods each side frame was slidden independently, to permit the placing of spools between them. Then the side frames were secured in a manner to prevent them from becoming displaced along these base-rods.

One of the base-rods or slideways aforesaid, upon which the separable frames were adjustably mounted, was caused to rotate by means of a train of mechanism that was driven by the usual line-spacing and carriage-returning lever of the machine, which in this case was an Underwood standard typewriter. This rotation of the rod was imparted to the aforesaid temporary winding spool, regardless of the position to which the mount may be adjusted along the rod.

In the present improvements the need of telescoping is eliminated and the temporary winding spool is splined to a stub-shaft, which is formed upon an arbor that is mounted upon the left-hand side-head or frame, and is geared to said rotating rod and its line-spacing train, whereby the temporary winding spool, of whatever length, is caused to revolve during the line-spacing operation. This arbor may have a spline, as for example its stub may be square in cross-section, and the spool-head may have a square hole to fit. Thus it will be seen that at all adjustments of the frames, in accommodating any width of tally-strip and tally-strip rolls, at any position along the platen, the temporary winding of the tally-strip and its superposed carbon may proceed automatically during the operation of typing the bill line by line, without the necessity of telescoping the side-heads together.

When a sufficient portion of the tally-strip has been typed, it is pulled off from the temporary winding spool, and at this time the portion of paid-off carbon may be wound back upon the carbon-spool; this rewinding being effected by means of a thumb-wheel and arbor which are provided preferably upon the

right-hand mount or frame, the arbor having a square shaft to fit in the square hole in the end of the carbon-spool.

For cheapness of manufacture, all spool-heads are made with square holes, and accordingly all of the stubs or gudgeons in the mechanism may be square, to fit said holes. Both gudgeons of the idly-revolving tally-strip-delivery spool may be squared, to fit the square holes in the heads of said spool. Permanent heads are secured upon the tally-strip and carbon-gudgeons, and the rolls consist of strip-windings upon headless cores, the cores having square bores to correspond with the gudgeons or stub-shafts.

The temporary rewinding spool does not need to be provided with spool-heads, as only a few turns of strip are ever wound upon the temporary winding spool, rendering heads unnecessary. This enables the tear-off knife to be placed comparatively close to the core of the rewinding spool.

According to the present improvements, it is only necessary for the branch office to carry a single kind of tally-strip mechanism in stock, for all customers. The branch office carries a stock of tear-off knives, all of which are of maximum length. In filling each order, the surplus length of knife is cut off, and the remainder is used as a tie-rod between the side-heads, without objectionable projection.

The provision of means for fastening any commonly-used width of tally-strip and carbon-strip to the wind-up roll is another feature of the present invention. There are provided two short inreaching fingers, one fastened to each stub-shaft of the wind-up roll and spaced a short distance outwardly from the core. These fingers are thus laterally adjustable for use with different widths of strips. Fastening the tally-strip and carbon-strip to the wind-up roll can be easily done by inserting the leading ends of these strips between the wind-up core and the inreaching fingers, and then folding short sections of the strips together back over the fingers.

Another advantage is afforded by provision of the inreaching tally-strip-fastening fingers. A typed section of the tally-strip and the overlying section of carbon-strip can be unwound from the wind-up core and the tally-strip held stationary while the carbon-strip is rewound on the carbon-strip core. Furthermore, the tally-strip thereafter can be conveniently manipulated for bringing it to cutting-off position relative to a cut-off knife provided on the tally-strip device.

Other features and advantages will hereinafter appear.

In the accompanying drawings,

Figure 1 is a fragmentary perspective view of the carriage of an Underwood typewriting machine having my tally-strip device applied thereto.

Figure 2 is a detail view, in cross-section, illustrating, in part, the construction of a brake-device for the carbon-feed-roll.

Figure 3 is a detail view, in cross-section, illustrating the construction of the latch-device for holding the carbon-feed-roll in operative position.

Figure 4 is a fragmental diagrammatic view of the carbon-strip and tally-strip as seen from the front, which illustrates the preferred arrangement of these strips relative to each other as they are wound up from the winding-up roll.

Figure 5 is a partial cross-sectional view of the structure shown in Figure 1.

Figure 6 is a front view, broken away in part, of the structure shown in Figure 1, which illustrates certain features of my tally-strip device.

Figures 7, 8, 9 and 10 are operational views, illustrating how certain functions of my tally-strip device are performed.

In an Underwood typewriting machine types 10 strike against a platen 11 on a platen-shaft 12, which is journaled in end plates 13 of a platen-frame 14. For guiding a worksheet, such as a bill 15, around the platen from the rear, a rear paper-table 16 and lower feed-rolls 17 are provided. The parts described hereinbefore may be of the same construction as in a standard Underwood typewriting machine.

For line-spacing the platen as the typing proceeds, a usual ratchet-wheel 20 is mounted on the platen-shaft 12, and a drive-pawl 21 is mounted on a slide 22 in the platen-frame 14. The slide 22 is pushed rearwardly upon operation of a usual line-space lever 23 and is returned by a retractile spring 24. The slide may have an upwardly-extending lug 25 to which is pivotally fastened the lower end of downwardly-extending arm 26 of a link-member which has a rearwardly-extending arm 27 integrally joined to the arm 26.

For mounting the tally-strip device on the typewriting machine, a bracket-plate 30 is mounted on each end plate 13 by screws 31. Extending between the bracket-plates 30 is a cross-rod 32 and a cross-shaft 33. For mounting the rod 32 in the brackets 30, a hole 34 is made in each bracket adjacent the upper edge at the rear of the bracket, and a slot 35 is cut through the rim around each hole. The rod 32 has a segmental portion cut away adjacent each end, so as to leave a neck-portion 36 arranged to pass through the slots 35. Each end portion of the cross-shaft 33 is journaled in holes in brackets 30 and is held against lateral displacement by outer collars 38 and inner collars 39, which are pinned to the shaft 33.

For rotating the shaft 33 step by step clockwise, a ratchet-wheel 40 may be fastened to the shaft adjacent the left-hand collar 39, and be integrally joined thereto, and a pawl

carrying member 41 may be rotatably mounted on the shaft and loosely fastened to the arm 26. A drive-pawl 42 is mounted on the member 41 for driving the ratchet-wheel 40.

To provide bracing means for the rod 32 and shaft 33 between the brackets 30, two stiffening plate-members 43 may be mounted on a usual crosswise platen-frame rod 44 extending between the end plates 13. Each of the plate-members 43 may have a forwardly-extending arm 45 carrying a rotatably-mounted roller 46 which bears against the platen 11. Each of the plate-members 43 may have an inreaching wrist 49. Between these wrists extends a cross-bar 50 which is detachably fastened to them by screws 51.

A collating table 52 having a leading-end gage in the form of a flange 53 is mounted for up-and-down adjustment on the cross bar 50 by means of elongated slots 54 and screws 55.

For mounting the feed-rolls and the take-up rolls for the tally-strip, designated as A, and the carbon-strip, designated as C, in my tally-strip device, a frame, generally designated as 60, includes right-hand and left-hand side-heads or frame-members 61 and 62, respectively, each of which is slidably mounted on the cross-rod 32 and the cross-shaft 33. To seat the frame-members 61 and 62 securely on the cross-rod 32, each member has a downwardly and rearwardly inclined mounting slot 63 cut in it to engage with a working fit over the cross-rod 32. A hole is provided in each frame-member for slidably engaging the cross-shaft 33. The frame-member 61 has a rigidly fastened hub 64 which engages around the cross-shaft 33. A collar 65 upon shaft 33 is adjustable therewith and can be fastened against the hub 64 in any adjusted position of the frame 60 by a set-screw 66.

The side-head 62 has fastened to its left face a hub 67 which engages about the shaft 33. Abutting the left face of the hub 67 is a gear-wheel 68 loosely mounted on the shaft 33. Secured to the gear 68 is a hub 70, which may have clutch-teeth 71, as indicated in Figure 1. A companion tooth clutch-member 72 for the hub 70 is mounted on the shaft 33. A pin-and-slot means may be provided like those disclosed in the co-pending application of Otto Thieme, Serial No. 304,653, filed September 8, 1928, for latching the clutch-member 72 out of engagement with the clutch-member 71, at will, against the pressure of a spring 73, which acts against a knurled thumb-piece 74 integrally joined to the clutch-member 72. A collar 75 is mounted on the shaft 33 for lateral adjustment therewith by a set-screw 76 and serves as a backing for the spring 73, which normally presses the clutch-member 72 into engagement with the clutch-member 71. By this arrangement, the gear 68 is operatively connected through

the shaft 33 to the line-space lever 23 for step-by-step rotation upon operation of the line-space lever.

- 5 Tally-strips and carbon-strips for use with the tally-strips are usually supplied wound on cores to form supply-rolls. According to one way of carrying out the present invention, the tally-strip and carbon-strip feed-rolls are wound on inexpensive paper-cores 80, which may have substantially square axial bores 81. A core 80 ordinarily adds very little to the cost of a roll of tally-strip or carbon-strip, and the core may be discarded when empty or bare. As will appear hereinafter, the empty core 80 from which the tally-strip A has been unwound can be used as a core for a wind-up roll on which both the tally-strip and the carbon-strip are wound as the work proceeds.
- 10 For mounting a tally-strip feed-roll, designated as 82, the core 80 of the feed-roll is slipped over the rod 32, and each end of the core engages on a short inreaching stub-shaft, generally designated as 84, which may be substantially square in cross-section for fitting snugly in the square bore 81. Each stub-shaft has an axial bore slightly larger in diameter than the rod 32, around which it engages a spool-head flange-member 85 and an integral hub-portion 86.
- 15 To provide a brake-means for the tally-strip feed-roll 82 for preventing the tally-strip from being unwound accidentally or too fast, a radial hole 87 is drilled in each hub-portion 86 and is tapped to receive a set-screw 88. The extreme bottom portion of the hole at each hub-portion is slightly reduced in diameter to form, in a well-known way, a kind of retaining flange whereby the steel ball 89, which fits loosely in the hole, can project slightly beyond the perimeter of the axial bore of the stub-shaft when the ball is pressed by a coil spring 90 disposed between the ball and the screw 88.
- 20 The pressure of the spring 90 forces the side of the wall of the stub-shaft axial bore opposite the ball against the rod 32, and the friction caused thereby acts as a brake to keep the feed-roll 82 from unwinding accidentally or any faster than the tally-strip is wound up. Provision of the friction-retarding means described hereinbefore also affords another advantage. Upon replacing a new tally-strip feed-roll on the cross-rod, 25 the right-hand stub-shaft 84 is slipped off the right end of the cross-rod, since the left end has an enlarged knurled head 91. When this is done, the above-described construction will prevent the ball 89 and spring 90 in the 30 right-hand stub-shaft from falling out of the stub-shaft. For mounting a carbon-strip feed roll, designated as 92, in the frame 60, two upwardly-directed mounting slots 93 are cut in the side frame-members 61 and 62, 35 each having lower ends for receiving a right-

hand stub-shaft 94 and a left-hand stub-shaft 95.

The stub-shaft 94 may include an inreaching substantially square body-member 96 for engaging tightly in a square bore of the 70 carbon-strip feed-roll core which may be like the core 80, an integral spool-head flange-member 97, an integral hub-portion 98 at the right of the flange-member 97, and a round bearing portion 99 coaxial with the hub-portion 98 and engaging in the slot 93 with a working fit.

Fitting closely against the right-hand face of the member 61 is a second hub-portion 100. At the right of the last-mentioned hub-portion a hard rubber or wood finger-wheel 101 may be fastened in any suitable manner on a reduced stem-portion 102 integrally joined to the hub-portion 100.

To latch the carbon-feed-roll 92 on the frame 60 against accidental displacement, as might be caused by sudden return of the usual platen-carriage, a latch-piece 103 (see Figure 3) is pivoted on a screw 104 in the frame-member 61. The upper end of the piece 103 is shaped to fit snugly down on the hub-portion 100 and has a finger-piece 105 to raise the latch against the pull of an over-center spring 106, which is also effective to hold the latch in released position. A stop- 85 plug 107 is provided to prevent the latch from being pulled too far by the spring 106 when the stub-shaft 94 is not in place on the frame 60.

The stub-shaft 95 includes an inreaching substantially square body-member 110, an integral spool-head flange-member 111 and a hub-portion 112.

To provide means to prevent accidental or too rapid unwinding of the carbon-strip C, a reduced coaxial key-portion 113 is integrally joined to the left face of the hub 112 and has the shape of a cylinder which has had a segmental portion cut away to form a flat face, such face on the key-portion 113 being designated as 114. Integrally joined to the left end of the key-portion 113 is a coaxial stem-member 115 whose outer end is threaded to receive a knurled head nut-member 116. Engaging around the key-portion 113 is a 110 knurled head bushing 117 which has a bore formed with a flat element for fitting snugly around the key-portion 113, which is thus secured to the bushing for rotation therewith.

The bushing 117 has a round bearing extension 119 which engages with a working fit in a lower enlarged circular portion 120 of the slot 93 in the frame-member 62. The outer end of the bushing 117 has an enlarged bore for receiving a washer 121 and an inner tubular shell-portion 122 of the nut-member 116. Disposed between the nut-member 116 and the washer 121 is a coil spring 123, which it can readily be seen, by inspec- 125 130

tion of Figure 6, is effective to press the bushing 117 and the hub-portion 112 against opposite faces of the frame-member 62. The above-described construction for keying the bushing 117 to the stub-shaft 95 is advantageous because of preventing the working loose of the adjustment of the friction means for preventing the accidental unwinding of the carbon C.

10 As the typing proceeds the tally-strip A and carbon-strip C are wound upon a single roll designated as 130, which may have a paper-core 131. This core may be, if desired, the same as the core 80 from which all of a 15 roll of tally-strip A has been unwound. The core 131 has a substantially square bore 132 and is mounted on two coaxially-disposed inreaching stub-shafts including a right-hand stub-shaft 133 and a left-hand stub-shaft 134.

The stub-shaft 133 may have a substantially square body-portion 135 which is of a shape and size to fit tightly in the square bore 132. Integrally joined to the right end of the body-portion 135 is a coaxial hub-portion 136, and an integral, coaxial reduced round bearing portion 137 extends from the right face of the hub 136 to engage with a running fit in a hole made to receive it in the frame-member 61.

To secure the stub-shaft to the frame-member 61 in a way to permit rotation of the stub-shaft, the bearing portion 137 has a coaxial hole tapped for receiving a screw 138 having 35 a suitable enlarged head for retaining a washer 139 against the right face of the frame-member 61.

The stub-shaft 134 includes a body-member 140 having a shape and size for fitting 40 tightly in the bore 132. A coaxial hub portion 141 is integrally joined to the left end of the body-member 140 and a coaxial bearing portion 142 engages with a running fit in a round hole provided in the frame-member 45 62 and extends a short distance past the left face of the same. A co-axial, integral reduced portion 143 at the left of the hub-portion 141 may be square in cross-section for having keyed thereon a gear-wheel 144 50 which meshes with the gear-wheel 68. A reduced coaxial extension 145 is integrally joined to the square portion 143 and has mounted thereon a hard rubber or wooden finger-wheel 146, the latter being held in place by a screw 147 which engages in a 55 tapped hole in a reduced neck-portion 148 of the finger-wheel. The right face of the neck-portion 148 may come against the gear 144 and help to hold the latter in place. A spacing washer 149 may be placed around the projecting part of the bearing portion 142 to prevent lateral movement of the stub-shaft 134 60 relative to the frame-member 62.

It will be noted that by the above-described 65 construction, the stub-shafts 133 and 134 are

secured to the frame-members 61 and 62, respectively, for lateral adjustment therewith and are rotatably mounted, and both are operatively connected to the line-space lever 23 for rotation thereby. It will also be noted that to adjust my tally-strip device for a different width of tally-strip, it is not necessary to separately manipulate the stub-shaft 133 or 134 in any way whatever, since they are moved closer together and further away by lateral movement of the frame-members 61 and 62.

The above construction of the feed-rolls and wind-up roll, each of which includes two stub-shafts and a core engaging the shafts with a splined relation, provides rolls which are securely mounted in the frame 60. Moreover, the carbon-feed-roll and the tally-strip take-up roll can each be easily and positively rotated in either direction by force applied to the finger-wheels at the ends of these rolls.

It is a feature of the present invention to provide means for attaching any commonly-used width of tally-strip A and a corresponding width of carbon-strip C to the wind-up roll 130. These means may include a pair of inreaching fingers or stub-plates 150, one finger being fastened by a screw 151 on the perimeter of the hub-portion 136, and the other finger being fastened by a like screw 152 to the hub-portion 141. The lengths of the strips will preferably be such as will bring their inreaching ends approximately even with or slightly past the inreaching ends of the stub-shafts 133 and 134. Each finger 150 will preferably be formed with a curvature transverse to its long axis which will make it substantially parallel to the curved periphery of the core 131.

The transversely-curved fingers 150 will be spaced away from the periphery of the core far enough to permit the tally-strip A and overlying carbon-strip C to be easily inserted between the fingers and the core. In most cases, it is preferable to space the fingers far enough away from the core 131 to permit the tally-strip and overlying carbon-strip to be straightened out, as indicated in Figure 8, and pulled up between the fingers 150 and the core 131 without causing a bend in the strips at the fingers, which would be detrimental to the thin relatively weak carbon-strip, especially if already used. Furthermore, it is desirable to prevent the carbon-strip from rubbing against the fingers when straightened out and moved up or back relatively to the core 131. The positioning of the fingers in this way also permits a special advantage which will appear hereinafter.

To secure the tally-strip A and carbon-strip C to the roll 130, short sections of the leading-end portions of the strips, after being passed between the fingers 150 and the

core 131, are turned or folded back over the fingers (Figure 5).

For severing the used portions in the tally-strip A, a cut-off knife is provided which includes a metal bar or blade 155 made preferably from stainless steel and having a knife-edge 156. For mounting this blade in the frame 60, an aperture 157 of a shape to receive the blade 155 with a snug fit is provided in the frame-members 61 and 62. A screw 158 engages in a tapped hole in each frame-member 61 and 62 and binds the blade 155 in the frame 60.

If desired, the blade 155 used with one of my tally-strip devices may be long enough for severing the widest tally-strips to be handled by that device, and when a narrower tally-strip is to be used, the frame-members 61 and 62 may be moved up nearer each other the desired distance and one or both ends of the knife-blade can project out beyond the frame-members 61 and 62. In many cases, however, two or more knife-blades 155 of different lengths will be furnished with each tally-strip device, the lengths of the blades corresponding with the widths of the tally-strips ordinarily to be used in the device.

In winding up the tally-strip A and the overlying carbon-strip C on the same feed-roll 130 some means is desirable to prevent typing of data on a work-sheet, such as the bill 15, after the rear end of the tally-strip (under the carbon-strip) has been unwound from its feed-roll 82 and drawn past the printing line. Should this occur no tally of the data will be made and also the platen may be smudged with carbon. To enable an operator to overcome these difficulties, it is preferred in my advice to have the tally-strip A project outwardly a short distance beyond one or both side edges of the overlying carbon-strip C (as is indicated in Figure 4), so that the tally-strip is always visible.

The use of my tally-strip device affords a special advantage when it is desired to use the carbon-strip C over and over again, as is often done. When a desired list of data has been copied on a section of the tally-strip A the roll 130 will be reversely rotated by one hand turning the finger-wheel 146, the clutch-teeth 71 having been first disengaged from the clutch-teeth 72. Then with the other hand the typed section of the tally-strip A and overlying carbon-strip C may be pulled forward, as indicated in Figure 7. The fingers 150 are then revolved around to come at the front of the core 131, as shown in Figure 8, and the typed section of tally-strip A and the overlying used section of carbon-strip C are pulled upwardly between the fingers 150 and the core 131 until the last item typed on the tally-strip is a suitable distance above the knife-blade 155. Then while the tally-strip is held in a straight position and stationary, and the feed-rolls 17 are released,

the carbon-roll 92 is reversely rotated by the operator's right hand turning the finger-piece 101 until the leading edge of the carbon-strip C is only a short distance above the fingers 150, as indicated in Figure 9.

The carbon-strip C and the tally-strip A are then folded over the fingers 150 and the wind-up roll 130 is rotated ahead by the finger-piece 146 until the tally-strip is brought to proper cutting-off position relative to the knife 155 on which it is severed in a well-known way, as indicated in Figure 10.

It will be noted that at all times during the above-described manipulation of the tally-strip A and carbon-strip C, they are both left under control of the finger 150, whereby they do not have to be reinserted after the tally-strip is cut off. It can also be seen that when desired the tally-strip A and the carbon-strip C may be severed together on the knife 155, and the severed portions may be removed from the tally-strip device while still wound on the core 131.

This result can be accomplished by simply unloosening the set-screw 66 and moving the frame-member 61 to the right, whereupon the right-hand finger 150 will be withdrawn from the roll of tally-strip and carbon-strip wound on the core 131. Then by moving the roll 130 to the right, it will be disengaged from the left-hand finger 150.

It is often required in typing bills 15 to keep a record of the bills on a record-sheet 160 which with an overlying carbon-sheet 161 may be fed through the typewriting machine under the bill 15 and over the tally-strip A. To permit use to be made of the arrangement of the tally-strip A and carbon-strip C, as shown in Figure 4 and explained above, when using a record-sheet 160, the right edge of the tally-strip A should extend slightly beyond the right edges of the bill 15 and the record-sheet 160.

Variations may be resorted to within the scope of the invention, and portions of the improvements may be used without others.

Having described my invention, I claim:

1. A tally-strip winding device for mounting upon the platen-frame of a typewriting machine and adjustable to use strips of various widths, including a pair of side-heads, means for supporting said side-heads, including a device extending along the platen and having at its ends means whereby it is attached to the platen-frame, one of said side-heads being independently adjustable along said supporting device, to vary the distance between said side-heads, an arbor journaled in one side-head and including an inwardly-projecting stub to serve as a mount for one end of a spool-core, and provided with splining means to enable it to rotate the spool-core, line-spacing mechanism connected to drive said arbor to wind the strip upon a core of any suitable length, and a stub projecting

inwardly from the other side-head to support the opposite end of the core for rotation, said stubs being separate and independent from each other and each being wholly carried by 5 its own side-head.

2. A tally-strip winding device for mounting upon the platen-frame of a typewriting machine and adjustable to use strips of various widths, including a pair of side-heads, 10 means for supporting said side-heads, including a device extending along the platen and having at its ends means whereby it is attached to the platen-frame, one of said side-heads being independently adjustable along 15 said supporting device, to vary the distance between said side-heads, an arbor journaled in one side-head and including an inwardly-projecting stub to serve as a mount for one end of a spool-core, and provided with splining means to enable it to rotate the spool-core, 20 line-spacing mechanism connected to drive said arbor to wind the strip upon a core of any suitable length, and a stub projecting inwardly from the other side-head to support the opposite end of the core for rotation, 25 and having splining means to enable it to be revolved by the core, said stubs being separate and independent from each other and each being wholly carried by its own side-head, 30 each of said stubs having a clip to catch the end portion of the strip, to connect the latter to the core.

3. Device constructed according to claim 2, having the opposite stubs correspondingly 35 splined, to enable the core to be reversed end for end.

4. A tally-strip winding device for mounting upon the platen-frame of a typewriting machine and adjustable to use strips of various widths, including a pair of side-heads, 40 means for supporting said side-heads, including a device extending along the platen and having at its ends means whereby it is attached to the platen-frame, one of said side-heads being independently adjustable along 45 said supporting device, to vary the distance between said side-heads, an arbor journaled in one side-head and including an inwardly-projecting stub to serve as a mount for one end of a spool-core, and provided with splining 50 means to enable it to rotate the spool-core, line-spacing mechanism connected to drive said arbor to wind the strip upon a core of any suitable length, and a stub projecting 55 inwardly from the other side-head to support the opposite end of the core for rotation, said stubs being separate and independent from each other and each being wholly 60 carried by its own side-head, one of said side-heads being also provided with a manually-rotatable arbor for winding a second core, and having a splined core-engaging stub, and the other-side-head having a companion stub projecting inwardly to support the other end 65 of the second core for rotation, the side-heads having means for detachably supporting the manually-rotatable arbor and the opposite companion stub, to permit detachment and replacement of the core, and there being 70 mounted in said side-heads opposite idly rotatable arbors having similar splined stubs to carry a delivery core and permit either core to be mounted upon either pair of stubs and reversed end for end.

port the other end of the second core for rotation.

5. A device constructed according to claim 4, all the stub-shafts being duplicates, to enable either core to be mounted upon either 70 pair of stubs and reversed end for end.

6. Device constructed according to claim 4, in which the side-heads have means for detachably supporting the manually-rotatable arbor and the opposite companion stub, to permit detachment and replacement of the 75 core.

7. A tally-strip winding device for mounting upon the platen-frame of a typewriting machine and adjustable to use strips of various widths, including a pair of side-heads, 80 means for supporting said side-heads, including a device extending along the platen and having at its ends means whereby it is attached to the platen-frame, one of said side-heads being independently adjustable along

said supporting device, to vary the distance between said side-heads, an arbor journaled in one side-head and including an inwardly-projecting stub to serve as a mount for one end of a spool-core, and provided with splining 85 means to enable it to rotate the spool-core, line-spacing mechanism connected to drive said arbor to wind the strip upon a core of any suitable length, and a stub projecting inwardly from the other side-head to support the opposite end of the core for rotation, said stubs being separate and independent from each other and each being wholly 90 carried by its own side-head, one of said side-heads being also provided with a manually-rotatable arbor for winding a second core, and having a splined core-engaging stub, and the other-side-head having a companion stub projecting inwardly to support the other end of the second core for rotation, the side-heads having means for detachably supporting the manually-rotatable arbor and the opposite companion stub, to permit detachment and replacement of the core, and there being 95 mounted in said side-heads opposite idly rotatable arbors having similar splined stubs to carry a delivery core and permit either core to be mounted upon either pair of stubs and reversed end for end.
